UNITED STATES PATENT OFFICE

WALTER S. DUWELIUS, OF CINCINNATI, OHIO

DESIGN FOR A GAME BOARD

Application filed May 13, 1932. Serial No. 43,793. Term of patent 7 years.

To all whom it may concern:

Be it known that I, WALTER S. DUWELIUS, a citizen of the United States, residing at Cincinnati, in the county of Hamilton and State of Ohio, have invented a new, original, and ornamental Design for a Game Board, of which the following is a specification, reference being had to the accompanying drawing, forming part thereof.

Fig. 1 is a perspective view, and Fig. 2 is a top plan view of a game board of my design.

I claim:

The ornamental design for a game board, as shown.
